United States Patent Office.

HENRY LIGHTY, OF ATTICA, INDIANA.

Letters Patent No. 95,119, dated September 21, 1869.

IMPROVEMENT IN WASHING-MACHINES.

The Schedule referred to in these Letters Patent and making part of the same.

To all whom it may concern:

Be it known that I, HENRY LIGHTY, of Attica, in the county of Fountain, and in the State of Indiana, have invented certain new and useful Improvements in Washing-Machines; and do hereby declare that the following is a full, clear, and exact description thereof, reference being had to the accompanying drawings, and to the letters of reference marked thereon, making a part of this specification.

The nature of my invention consists in the construction of a washing-machine, which is provided with a movable ribbed bottom, and a rubber-head which runs on rollers, for the purpose of lessening the labor, as will hereafter be fully set forth.

Figure 1 is a plan view of my invention.

Figure 2 is a section view of the same.

Letter A represents the frame of the machine, which may be of any desired shape, and which is provided with a movable bottom, B, the sides of which extend about one-half way up the frame, and serve as a track, upon which the rollers of the rubber-head run.

This bottom consists of a number of narrow curved ribs, which rise abruptly at one end, as seen in fig. 2, and which serve to hold the clothes up from the bottom, and to prevent them from coming in contact with the dirt which is washed from them, and which settles down between the ribs. These ribs are joined together at the ends by cross-pieces, which have hand-holes in them, so that the whole bottom can be raised up from the water, so as to wring the clothes out.

The frame A is provided with a handle at each corner, so that it can be easily carried from one place to another, and has a cleat, C, placed inside, at two of the corners, so as to prevent the bottom B from being displaced.

The rubber-head, or beater D has a number of arms, or prongs E, extending downward from it far enough

to touch the ribs, which are used to wash the clothes, both by rubbing and beating. Upon each end of the head there is placed a roller, G, which runs along upon the top of the movable bottom B, so as to lessen the exertion of moving it back and forth.

Extending back from the head, there are two curved arms, H, the ends of which are joined together by the handle K. Secured to the ends of the handle are two bars, L, which extend backward, and are fastened to the cross-piece N.

Rising up from the sides of the frame, there are two standards, M, which have two or more notches formed in their tops, so as to receive the ends of the cross-piece N.

After the bottom has been raised above the water, the beater, or rubber can be used to force the clothes against the raised ends of the ribs, where the water is pressed out of them, without the trouble of wringing.

This machine is peculiarly adapted to washing wool in the fleece without breaking it, and to pressing the water from it, in the same manner as the clothes. The cover extends over but a portion of the frame.

Having thus described my invention,

What I claim, and desire to secure by Letters Patent, is—

The combination of the tub A, movable bottom B, beater D, rollers G G, arms H H, rods L L, cross-shaft N, and standards M M, all substantially as and for the purposes specified.

In testimony that I claim the foregoing, I have hereunto set my hand, this 1st day of June, 1869.

HENRY LIGHTY.
